UNITED STATES PATENT OFFICE.

FRANK M. FABER, OF PITTSBURG, PENNSYLVANIA, ASSIGNOR TO
WILLIAM S. ELLIOTT, OF PITTSBURG, PENNSYLVANIA.

TURBINE FOR BOILER-CLEANERS.

No. 826,413.

Specification of Letters Patent.

Patented July 17, 1906.

Application filed March 10, 1903. Serial No. 147,068.

To all whom it may concern:

Be it known that I, FRANK M. FABER, of Pittsburg, Allegheny county, Pennsylvania, have invented a new and useful Turbine for Boiler-Cleaners, of which the following is a full, clear, and exact description, reference being had to the accompanying drawings, forming part of this specification, in which—

Figure 1 is a side elevation of my improved turbine-cleaner with the turbine and case in section. Fig. 2 is a front elevation of the case. Fig. 3 is a side elevation of the same broken away to show the vanes; and Fig. 4 is a rear end elevation, partly in section.

My invention relates to the class of tube-cleaners wherein a fluid-actuated turbine is employed to drive the cleaning-tool, more especially to the Elliott type of cleaner, wherein freely-swinging longitudinal arms with transverse cutting-disks are used, though the invention may be used with any desirable type of cleaner.

The invention is designed to improve the structure of the turbine-case and contained parts, to provide a collecting-chamber for leakage, which will prevent water being forced into the journal, and to provide a thrust-bearing for the cleaner-shaft.

In the drawings, 2 is the turbine-case of cylindrical form with a hose-coupling 3 screwed within its rear end.

4 is the turbine-wheel proper, having curved passages 5 in its periphery, which are closed at the outer side by the inclosing band or ring 6, with a beveled inner face secured by screws 7 extending between the passages. The stationary portion 8 of the casing has the feed-passages 9, with an inclosing band 10, secured by screws 11, this band having a beveled inner face similar to that on the turbine-wheel. This stationary feed portion is held within the case by radial projections 12, secured to the case 2 by screws 13. The turbine-shaft 14 is provided with a projecting collar 15, resting against the annular flange 16 of the bushing 17. The bushing 17 is held by inwardly-projecting bearings or ring portions 8' of the casing 8. The shaft has the larger threaded portion 18 screwing within the turbine shell and the smaller threaded portion 19, to which the universal joint 20 is screwed.

Between the turbine-shell and the stationary portion extending within it is provided

an annular chamber 21, with outlet-holes 22 leading to the exterior of the case through the turbine-wheel. Any water which leaks in between the stationary feed-passages and the turbine-vanes at the transverse joint will enter this chamber and pass out through the hole, and thus be prevented from forcing backwardly and carrying gritty sediment into the journal.

The turbine-shaft 14 extends at its rear end into a chamber 23, formed within the rear portion of the stationary turbine part, and to resist the tendency to draw this shaft forwardly and out of the case, caused by the high pressure of the water, I provide a thrust-bearing within this chamber. The part of the shaft within the chamber is threaded, a nut 24 being screwed upon it. Between this nut and the front wall of the chamber are alternate disks 25 of bronze and 26 of steel. The forward steel disk has projecting lugs 27, which engage corresponding recesses in the front wall of the chamber. These thrust-disks loosely surround the threaded shaft and may be tightened or loosened by turning the nut. The nut is held in adjusted position by the locking-washer 28, having bent projections engaging notches in the nut and held by lock-nut 29. The rear end of this thrust-bearing chamber is closed in by the screw-cap 30 to prevent access of the water to the bearing and to close the chamber 85 and enable the bearing to run in oil.

The advantages of my invention result from the use of the annular leakage-chamber with its outlet, from the thrust-bearing, which takes up the pull on the shaft, from the inclosed grease-chamber for the bearing and means for adjustment, and the general arrangement of the case and its parts.

Many variations may be made in the form and arrangement of the head, the case, and the contained parts without departing from my invention.

I claim—

1. In a turbine, a case having a fluid-chamber in its rear portion and a stationary turbine part in front of said chamber with fluid-supply passages extending through it in annular form, a turbine-shaft extending rearwardly through the body of the stationary turbine part and terminating in a central thrust-bearing chamber, a thrust-bearing

- within said chamber and a cap for the chamber arranged to close its rear end; substantially as described.
2. In a turbine, a case having a fluid-chamber in its rear end, a rear supply-opening, a central thrust-bearing chamber in front of the fluid-chamber, and having a removable cap, a turbine-shaft having a thrust-bearing within said chamber and a bushing surrounding the shaft; and extending forwardly from a point near the thrust-bearing chamber for a major portion of the distance to the end of the case to thereby provide an elongated bearing for the shaft substantially as described.
3. In a turbine, a case having a fluid-chamber in its rear portion with a rear supply-passage, a stationary rearwardly-elongated turbine part in front of said chamber and having fluid-supply passages arranged in annular form, a turbine-wheel in front of the stationary turbine part and having a shaft extending rearwardly through the center of the stationary turbine part, a thrust-bearing at the rear end of the shaft within a central chamber, and a rear removable cap for said chamber in line with the rear supply-passage; substantially as described.
4. In a turbine, a case having a rear fluid-chamber with a rear supply-opening, a stationary turbine part in front of said opening and having a thrust-bearing chamber therein, a turbine-wheel in the front end of the case having a central shaft extending back through the stationary turbine part and terminating in the thrust-bearing chamber, and a central cap for the rear end of the chamber, the turbine-wheel to be screwed against a shoulder on the shaft, said shaft having a projecting stub at the front end beyond the turbine-wheel for attachment of a tool; substantially as described.
5. In a turbine, a case containing a turbine-shaft extending centrally within an elongated stationary turbine part, a removable bushing between the shaft and stationary turbine part, and a rear thrust-bearing for the shaft within a chamber having a removable cap; substantially as described.
6. In a turbine, a case containing a turbine-shaft extending centrally within a stationary turbine part and having an extended bearing therein, a removable bushing between the shaft and stationary turbine part, and a rear thrust-bearing for the shaft within a chamber having a removable cap-closure; substantially as described.
7. In a turbine, a case containing a stationary turbine part having annular supply-ports, a turbine-wheel in front of the stationary part and screwed against a shoulder on the turbine-shaft, said shaft extending back through the stationary turbine part, a removable bushing between the shaft and stationary turbine part, and a rear thrust-bearing for the shaft within a chamber having a removable cap-closure; substantially as described.
8. In a turbine, a case containing a stationary turbine part having supply-passages in annular form extending through it and communicating with a rear water-chamber having a rear supply-opening, a front turbine-wheel secured against a shoulder on a turbine-shaft, said shaft extending rearwardly and centrally through the stationary turbine part, a removable bushing between said shaft and the stationary turbine part, a central thrust-bearing chamber inclosing the rear portion of the shaft, and a removable rear cap for said thrust-bearing chamber; substantially as described.
9. In a turbine, a body having a stationary turbine portion of annular shape with water-supply ports extending longitudinally through it and communicating with a rear water-chamber, a front turbine-wheel secured against a shoulder on a turbine-shaft, said shaft extending back through the central hole in the stationary turbine part, a thrust-bearing at the rear end of said shaft, a chamber within the stationary turbine part inclosing said thrust-bearing, and a rear end cap for said chamber; substantially as described.
10. In a turbine, a body having a stationary turbine portion of annular shape with water-supply ports extending longitudinally through it and communicating with a rear water-chamber, a front turbine-wheel secured against a shoulder on a turbine-shaft, said shaft extending back through the central hole in the stationary turbine part, a thrust-bearing at the rear end of said shaft, a chamber within the stationary turbine part inclosing said thrust-bearing, and a rear end cap for said chamber, said cap being screwed into the stationary turbine part; substantially as described.
11. In a turbine, a body having a removable coupling screwed into its rear end, a water-chamber into which the coupling leads, and a central turbine-shaft having a thrust-bearing chamber with a removable central rear cap, thrust-bearing rings in said chamber, the opening for said cap being of a diameter at least as large as the thrust-bearing rings and a bushing surrounding the shaft and extending forwardly from a point near the thrust-bearing chamber for a major portion of the distance to the end of the body to provide an elongated bearing for the shaft and having a collar on one end thereof engaging a portion of the body; substantially as described.
12. In a turbine, a case or body having a fluid-chamber at its rear end, a fixed turbine portion having therein a thrust-bearing chamber, a turbine-shaft extending rearwardly through the stationary turbine port-

tion and terminating within the bearing-chamber, a turbine-wheel secured to said shaft, an annular leakage-chamber communicating with the joint between the turbine-wheel and the stationary turbine portion and having an outlet leading through the wheel, and a removable cap closing the rear end of the thrust-bearing chamber, said cap protecting the bearing-chamber from the rear, and the leakage-chamber guarding against the entrance to the bearings of water and grit from the front; substantially as described.

13. In a turbine, a case or body having a fluid-chamber in its rear end with a rear supply-opening, a central thrust-bearing chamber in front of the fluid-chamber and having a removable cap, and a turbine-shaft having a surrounding removable bushing extending

15 from a point near the thrust-bearing chamber forwardly for a major portion of the distance to the end of the case to form an elongated bearing for the shaft, and formed at

one end with a collar engaging a portion of the case or body, said shaft being provided with a thrust-bearing within the thrust-bearing chamber, said thrust-bearing having a series of rings; substantially as described.

14. In a turbine, a body having a thrust-bearing chamber provided with a removable cap, means for permitting the passage of fluid around the thrust-bearing chamber, a shaft provided with a turbine member and having a thrust-bearing in the thrust-bearing chamber, and a bushing surrounding the shaft and extending forwardly from a point near the thrust-bearing chamber for a major portion of the distance of the end of the body to provide an elongated bearing for the shaft, substantially as described.

15 In testimony whereof I have hereunto set my hand.

FRANK M. FABER.
